UNITED STATES PATENT OFFICE.

JAMES O. BEWAN, OF SAVANNAH, GEORGIA.

GAME-COUNTER AND CARD-CABINET.

No. 835,844.

Specification of Letters Patent.

Patented Nov. 13, 1906.

Application filed November 16, 1904. Serial No. 233,046.

To all whom it may concern:

Be it known that I, JAMES O. BEWAN, a citizen of the United States, residing at Savannah, in the county of Chatham and State 5 of Georgia, have invented a new and useful Improvement in a Game-Counter and Card-Cabinet, of which the following is a specification.

This invention is a game recorder and 10 counter, the object being to provide a simple and efficient device by means of which the points of a game can be counted and also the number of games recorded.

Another object is to provide a counter and 15 recorder of such construction that the score of the player can be indicated irrespective of whether the player is scoring points or receiving setbacks.

Another object of the invention is to provide 20 a construction which can be applied to an individual recorder and counter and also to a device adapted for the use of a number of players, and a still further object is to provide a recorder and counter of such construction 25 that it can be embodied in a cabinet and frame which can be used for advertising purposes.

With these various objects in view the invention consists in the novel features of construction and combination hereinafter fully 30 described, and pointed out in the claims.

In the drawings forming a part of this specification, Figure 1 is a top plan view of a recorder and counter constructed in accordance 35 with my invention, the door of the cover being raised for the purpose of exposing the card-holders. Fig. 2 is a longitudinal sectional view on the line 2 2 of Fig. 1. Fig. 3 is an irregular section on the line 3 3 of Fig. 1. Fig. 4 is a detail sectional view on the line 4 4 of Fig. 3. Fig. 5 is a detail perspective view 40 of the card-holder. Fig. 6 is a perspective view showing an individual recorder and counter.

The principle of my invention is applicable 45 to an individual game counter and recorder and also to one intended for the use of a number of players, and in Fig. 1 I have shown a device constructed for the use of four players; but it is obvious that counters 50 can be made for any desired number of players; but inasmuch as four is the usual number playing at one time I have adopted this type as the best one for illustration.

In the practical embodiment of my invention 55 I employ a base A, preferably rectangular

lar in shape, although it may be of any desired shape and also any convenient size, and fitting upon the cross-strips A' is a cabinet B, which is also made of any desired material 60 and shape and which is adapted to contain the operating mechanism of the counter and recorder. The base is preferably provided with ash-trays C, hinged at C', whereby the said trays can be turned outwardly for the 65 purpose of discharging the ashes therefrom. These trays are provided with strips C², upon which the cigar is supported. The cabinet B is provided with a top D, which is preferably detachable therefrom, so that in case 70 any part of the mechanism should become deranged the top can be removed for the purpose of rearranging the same, and at the rear end the top is provided with an upwardly-opening hinged door E, so that the cards F, 75 held in the holders G at the rear of the cabinet, can be removed therefrom, the construction and operation of said holders being hereinafter more fully explained.

I will now proceed to describe the counting 80 and recording mechanism, and inasmuch as the mechanism is the same throughout for each player, the description of one mechanism will be sufficient for the entire device. The top D has four openings D', D², D³, and 85 D⁴ produced therein, said openings being in longitudinal alinement with one another, and the openings D' and D² constitute one pair enlarged at their opposite ends, and the openings D³ and D⁴ constitute another pair enlarged at 90 their opposite ends. Adjacent the opening D' is printed the word "player," and adjacent the opening D² is printed the word "games." Through the opening D' is displayed a portion 95 of an endless belt H, upon which is marked the letters of the alphabet or any other suitable character for the purpose of designating the name or initial of the player, and through the opening D² is displayed a portion of an endless belt H² having any desired number of numerals marked thereon for the purpose of indicating the number of games, and through the openings D³ and D⁴ are displayed portions of endless belts H³ and H⁴ containing numerals for the purpose of indicating the number of points scored during any particular game, and the numerals upon these belts can be so arranged and of such denominations that scores of any magnitude can be had.

The endless belts H', H², H³, and H⁴ travel upon spools I, loosely mounted upon the hori-

zontal shaft K, which is journaled in the upper portion of the cabinet, said spools being so arranged that one character upon each belt will be displayed at its respective opening, and each spool is provided with a milled disk I' at one end, which occupies the enlarged end of the opening and projects a short distance above the face of the top, so that the spool can be easily manipulated for the purpose of moving the belt in either direction. Each belt passes around a roller L, mounted upon a shaft M, up over the collar N, mounted upon a shaft O, and around a roller P adjacent the roller L, mounted upon a shaft Q. Two rollers M and P are employed at the bottom of the case and the one roller N at the top in order to permit the belt to be made of sufficient length to carry the desired number of numerals. It is obvious, however, that two of the rollers can be omitted and the belt caused to travel around only the spool I and the roller L at the bottom. The belt H' is preferably made with only a single flight, as most clearly shown in Fig. 3, for the reason that this belt is only expected to have twenty-six characters marked thereon. Depending guide-flanges I² serve to hold each pair of spools I in their proper positions, and milled disks I', together with the depending flanges I², also serve to hold each pair of rollers M in their proper positions, and inasmuch as the rollers are held in their proper positions the belts will of course properly travel. At the bottom of the cabinet the rollers L and P are held in their proper positions by means of a series of spacing-fingers R, punched in a strip R', which extends across the bottom of the cabinet and turned down around the cross-strip A', as shown at R². The sides of the cabinet are slotted where the shafts O, M, and Q pass through, and bearing-blocks S are inserted for the purpose of taking up any slack in the belts. Thus it will be seen that by turning the disk in the opening D' the belt can be moved so as to bring any particular character into the opening, and in the present instance the letter A is shown, and by moving the disk in the opening D² the desired numeral can be brought into the opening for the purpose of indicating the number of games, and in the present instance the numeral 2 is shown. By moving the disks in the openings D³ and D⁴ the proper number of points can be brought to view, and in practice I prefer to arrange the numerals from "1" to "50" upon each belt, so that taking the two belts as one a score as high as five thousand and fifty can be made.

Inasmuch as there are games in which a player can be set back as well as pointed forward, it becomes necessary to indicate by means of the recorder whether the player is progressing or being set back, and for this purpose I produce two openings T and T' in the top of the cabinet directly above the

openings D³ and D⁴ and connect them by means of a slot T², and working in the slot is a knob T³, carrying a slide T⁴, which has upon the left-hand end the letter "S" to designate set-back, and upon the right-hand end the letter "P" to indicate the points and by shifting the knob T³ the letter "S" or "P" can be displayed, indicating that the player has received a set-back or a definite number, and in the present instance this set-back is indicated by the numeral 25.

In the construction shown in Fig. 6 all of the parts operate in substantially the same manner, and it is only necessary to have one opening and belt indicating the games and two openings and belts for the purpose of indicating the score, as the individual player will keep his counter by him, and it will therefore not be necessary to have any belt for designating the particular player. The adjustable slide for indicating the set-back and points is exactly the same as the construction before referred to.

It is of the utmost importance that one or more packs of cards be kept with each game counter and recorder, and it is also important that each pack be kept in a compact form, and for this purpose I have arranged a card-holder G at the rear of the case, which card-holder preferably consists of two inverted-U-shaped spring-metal bails G, connected to the strip G², arranged in the bottom of the cabinet, the pack of cards F being inserted between these spring members, as most clearly shown in Fig. 3, and connected to the inner member is a ribbon G³, which is of sufficient length to extend entirely down to the strip G² and upwardly over the rear end of the cabinet, as shown in Fig. 3, the cards resting upon this piece of ribbon when in place, and when it is desired to remove the cards from the cabinet the door E is raised, and by pulling upon the ribbon the cards can be elevated and projected through the opening in the top. The memorandum-cards, of celluloid or any other suitable material, can be arranged upon the inner face of the door E, and upon which notes or memoranda relating to the games can be written.

From the above description, taken in connection with the accompanying drawings, it will be seen that I provide a simple and efficient game counter and recorder which will operate in the manner described and for the purpose set forth.

Having thus fully described my invention, what I claim as new, and desire to secure by Letters Patent, is—

1. In a game counter and recorder, a base having a cabinet arranged thereon, the top of said case or cabinet having a plurality of openings therein, an upwardly-opening hinged door constituting part of the top, a card-holder arranged within the cabinet below the door, and means connected with said

card-holder for projecting the cards through the door, the endless belts arranged within the cabinet, and adapted to have portions thereof displayed through the openings, together with means for moving the said belts as set forth.

2. In a game counter and recorder, a top having a plurality of openings through which are displayed characters indicating the num-

ber of games and points, said top also having the openings T, and T', connected by a slot T², and a slide T⁴, movable by the knob T³, said slide having characters thereon, to indicate set-back and points.

JAMES O. BEWAN.
